UNITED STATES PATENT OFFICE

MICHAEL DERMODY, OF NEW YORK, N. Y.

LATCH

Application filed February 13, 1928. Serial No. 254,088.

This invention relates to latches and particularly to an improvement in knob-actuated door latches.

One of the principal and outstanding objects of the present invention is to provide a door latch which is so constructed as to eliminate the expensive mortising operation which is ordinarily required in associating the latch with a door.

10 The invention further comprehends a latch mechanism which is comparatively simple in its construction, inexpensive to manufacture, easily applied to the door, and which is highly efficient in its purpose.

15 With the above recited and other objects in view, reference is had to the following description and accompanying drawings in which there is exhibited one example or embodiment of the invention, while the appended claims define the actual scope of the invention.

In the drawings—

Figure 1 is a fragmentary vertical sectional view through the improved latch applied to a door stile and illustrating the latch bolt in its normal projected position;

Fig. 2 is a transverse sectional view therethrough taken approximately on the line 2—2 of Fig. 1;

30 Fig. 3 is a fragmentary horizontal sectional view illustrating the manner in which the latch bolt is locked in its projected position against retraction;

Fig. 4 is a fragmentary side view of the door stile prior to the application of the latch thereto;

Fig. 5 is a fragmentary top plan view of the latch bolt;

Fig. 6 is a detail cross sectional view taken approximately on the line 6—6 of Fig. 3 and particularly illustrating the spring seat.

Referring to the drawings by characters of reference, A designates the stile of a door or other swinging closure. The latch constituting the present invention includes generally the latch bolt assemblage designated generally by the reference character B and the latch bolt actuating means designated generally by the reference character C. The 45 latch bolt assemblage B includes a bolt com-

prising a circular shank 10, having an enlarged head 11 at one end, which defines a shoulder 12 at its juncture with the shank. The latch bolt assemblage further includes a casing in the nature of a circular sleeve 13 carried by a plate 14, which sleeve is formed at its juncture with the plate with a substantially squared portion 15, within which the head 11 of the bolt is adapted to be retracted and from which the same is designed to be 50 partially projected so that the head may engage with a suitable form of keeper (not shown) in a door frame or the like. Adjacent its rear or inner end, the sleeve or casing 13 is provided with diametrically disposed upper and lower slots 16 and 17, portions of the material from the slots being bent inwardly at 18 to define spring seats. A coiled expansion spring 19 surrounds the bolt shank 10 and has its opposite ends bearing 55 respectively against the spring seats 18 and the shoulder 12 so as to function to normally project the bolt head beyond the outer surface of the plate 14. The bolt shank 10 adjacent its rear end is provided with a slot 20 for a purpose to be hereafter set forth. Under this construction and arrangement of the latch bolt assemblage B, it is obvious that the same may be associated with the door stile A or other swinging closure by boring a hole D inwardly from the outer free edge of the stile and forming the outer end of the hole with a squared portion E, while the outer edge of the stile is mortised out at F 70 merely to a depth equal to the thickness of 60 the plate 14.

The latch bolt actuating means C includes a spindle 25 preferably of square or non-circular formation, upon which a circular collar 26 is arranged for turning movement with the spindle. The door stile A is formed with a transverse circular bore G, which communicates with the hole D adjacent its inner end, which bore G constitutes a bearing for the collar 26. The opposite ends of the spindle 25 extend through escutcheons 27 and 28 secured to the opposite side faces of the stile A and the portions of the spindle which project beyond the escutcheons have attached thereto knobs 29. The collar is formed 95

with a radially projecting actuator pin 30 which is designed to project through the slot 16 in the bolt sleeve and to engage in the slot 20 of the bolt shank. The pin in addition to serving as a means for retracting the bolt head 11 against the action of the spring 19, also serves as a means for limiting the outward projection of the bolt. In order to facilitate the association of the latch bolt actuating means with the door stile, and with the latch bolt assemblage, the stile is provided with a radially and angularly disposed notch H which communicates with the transverse bore G.

In assembling the latch with the door stile, the bolt sleeve 13 with the latch bolt in a normal position is inserted in the hole D until the inner slotted end 16 is disposed approximately in alignment with the actuator pin 30, which is turned forwardly at a forty-five degree angle. The spindle 25 and sleeve 26 are then turned until the pin 30 engages in the slot 20. The plate 14 is then shoved home until it lies within the mortise F, and screws or other fastening devices I are employed for securing the latch bolt assemblage in place. It is thus obvious that by turning the knob in one direction, the actuator pin engaging in the slot 20, will effect a retraction of the bolt against the action of the spring 19, while release of the knobs will permit the spring to function to project the latch bolt head 11.

In order to lock the bolt against retraction, a locking pin 31 is insertable through an opening 32 extending through the inner portion of the door stile and through an opening 33 in the bolt cylinder 13. The pin is disposed directly in rear of the latch bolt shaft 10 and intersects its path of movement so as to prevent retraction of the bolt from the outer side of the door.

What is claimed is:

1. A bolt guide member adapted to be inserted in a bore extending inwardly from the edge of a door stile, a bolt in the guide and a rotatable bolt operating member adapted to be accommodated in a transverse bore intersecting the first mentioned bore, the operating member including means engageable with or disengageable from the bolt upon rotation of said member, only when the bolt casing is partially withdrawn from its bore.

2. A bolt guide member adapted to be inserted in a bore extending inwardly from the edge of a door stile, a bolt in the guide and a rotatable bolt operating member adapted to be accommodated in a transverse bore intersecting the first mentioned bore, the operating member including means engageable with or disengageable from the bolt upon rotation of said member, only when the bolt casing is partially withdrawn from its bore and said bolt casing when in home position preventing disengagement of the bolt and its actuating means without preventing recip-

rocation of the bolt by its actuating means.

3. A bolt guide member adapted to be inserted in a bore extending inwardly from the edge of a door stile, a bolt in the guide and a rotatable bolt operating member adapted to be accommodated in a transverse bore intersecting the first mentioned bore, the operating member including means engageable with or disengageable from the bolt upon rotation of said member, only when the bolt casing is partially withdrawn from its bore, said means comprising a finger fixed to the rotatable member and engageable in a cutaway portion of the bolt.

4. In a latch, a sliding bolt and a bolt casing, a rotatable bolt actuating member, the axis of rotation of which is disposed substantially at right angles to the bolt, and means for operatively coupling said member with the bolt or uncoupling it from the bolt by a rotary movement of said member only when the bolt casing is in a predetermined position.

Signed at New York in the county of New York and State of New York, this 10th day of February 1928.

MICHAEL DERMODY.
